Attorney, Agent, or Firm—James C. Simmons

[57] CLAIM

The ornamental design for a convertible chair, substantially as shown and described.

DESCRIPTION

FIG. 1 is a front perspective view of a convertible chair showing my design.

FIG. 2 is a rear perspective view thereof.

FIG. 3 is an enlarged front perspective view wherein the seat and backrest cover has been removed to convert the chair into position for use as a loom.

The broken line disclosure of a shuttle, shuttle yarn, warp yarn, and heddles are for illustrative purposes only.

FIG. 2
